UNITED STATES PATENT OFFICE.

ROBERT H. COWDREY, OF CHICAGO, ILLINOIS.

SAFETY CUT-OFF.

1,085,245.

Specification of Letters Patent. Patented Jan. 27, 1914.

Application filed October 30, 1911. Serial No. 657,601.

To all whom it may concern:

Be it known that I, ROBERT H. COWDREY, a citizen of the United States, residing at Chicago, in the county of Cook and State 5 of Illinois, have invented certain new and useful Improvements in Safety Cut-Offs, of which the following is a specification.

This invention relates to improvements in safety cut-off devices, particularly adapted, 10 though not necessarily limited in its use, to automatically stop or check the flow of gas passing therethrough, and one of the objects of the present invention is to provide an improved, simple, durable and cheap device of 15 the class which is adapted to be automatically actuated by an abnormal flow or movement of the fluid as contradistinguished from pressure, and which actuation would not be reliable if the pressure is depended 20 upon, inasmuch as the pressure varies considerable and at almost any moment; a further object being the provision of means whereby the device may be positively and 25 manually actuated at will to stop or check the flow.

A further object is the provision of an improved device of this class, having means whereby the device may be adjusted or set 30 to meet the varying conditions in the rate of flow of the fluid found in different localities and when different styles of meters are employed.

To the attainment of these ends and the accomplishments of other new and useful objects, as will appear, the invention consists 35 in the features of novelty in substantially the construction, combination and arrangement of the several parts hereinafter more fully described and claimed, and shown in 40 the accompanying drawings illustrating an example of the invention, and in which—

Figure 1 is a vertical sectional view of an improved device of this class constructed in accordance with the principles of this invention; Fig. 2 is a front elevation of Fig. 1 with the protecting casing removed; Fig. 3 is a side elevation of the cam and stop for limiting the opening movement of the valve and by means of which the valve may 50 be positively and manually closed; Fig. 4 is a front elevation of Fig. 3; Fig. 5 is a view partly in elevation and partly in section, showing the manner in which an improved device of this class may be installed 55 and the mechanism for manually operating the valve; Fig. 6 is a view partly in eleva- 60 tion and partly in section and with parts removed showing the operating handle and its connection for manually operating the valve; Fig. 7 is a view similar to Fig. 1 showing a portion of the closure for the casting in which the operating mechanism is located, and the operating handle showing 65 the parts in another position from that shown in Fig. 6; Fig. 8 is a sectional view on line 8—8—, Fig. 6; Fig. 9 is a plan view of the valve seat; Fig. 10 is a detail view showing another connection between the operating mechanism and the cam.

This improved device is adapted to be 70 located at any point in the service pipe, but preferably in close proximity to the gas main valve and at a point where access may be readily had thereto.

Referring more particularly to the drawings, the valve casing is preferably constructed of two sections, 15—16, detachably secured together by suitable fastening devices 17. The section 15 is provided with an offset portion 18 which has communication with the valve chamber 19, the wall of which latter is shaped to permit a free movement of the valve. The section 16 is provided with a chamber 20, which communicates with the offset portion 18, and also an outlet chamber 21 which communicates with the valve chamber 19. The fluid enters the valve chamber 19 through the supply pipe 22, which has communication with the valve chamber and flows out of the casing 15 through the outlet pipe 23, which latter has communication with the outlet chamber 21. A valve seat designated generally by the reference number 24, (see particularly Fig. 9) is detachably connected, preferably at 95 the inner face of the section 16 by means of suitable fastening devices 25, so that when the section 16 is removed from the section 15, access may be readily had to the valve seat. This valve seat is preferably provided with projecting ears or lugs 26 which extend into the offset portion 18, and between which ears or lugs the valve 27 is pivotally mounted as at 28. This valve 27 moves in the valve chamber 19 toward and 100 away from the valve seat 24, and is provided with a counter-weight 29, which latter is of a weight a little less than the weight of the valve 27 on the opposite side of the pivot 28, so that the normal tendency of the valve 27 105 will be to move away from the valve seat 24 to open the valve.

The valve being pivotally connected to the valve seat, and the valve seat itself being detachably connected with the section 16 of the valve casing; it will be manifest that 6 when the section 16 is detached, the valve seat 24 and the valve 27 together with the counter-weight 29, will also be removed, and by inverting the section thus removed, access may be readily had to the valve seat 10 and the valve without dismantling all of the other parts of the mechanism. In order to limit the opening movement of the valve 27, a stop 30 is provided which is preferably in the form of a cam having a cam face 31. 15 This stop 30 is provided with an axle 32 rotatably mounted in a suitable bearing which is provided with packing 33 to form a fluid tight joint. The stop is located in close proximity to the valve so that when it is in 20 its open position, it will engage the cam face 31, and when the stop is rotated by rotating its axle 32, the cam face 31 will be adjusted to present different portions to the valve and the degree of the opening movement of the valve will consequently be controlled by the position of the cam face with 25 respect to the valve.

The stop 30 may be adjusted in any suitable manner preferably by means of a lever 34 which is connected with the axle 32 of 30 the stop on the outside of the valve casing. This lever is of some width and is provided with a series of apertures or openings 35 therein adapted to receive a stop lug 36, 35 which lug coöperates with the stop 37. When it is desired to adjust the stop 30, the stop lug 36 is placed in the proper opening 35, according to the position in which it is desired to maintain the valve 27, and the 40 stop will be held in its adjusted position by the engagement of the stop lug 36 with the lug 37.

As indicated by the arrows in Fig. 1, the fluid enters the device through the supply 45 pipe 22 and finds its way out through the service pipe 23, and the valve 27 will normally rest in an open position against the stop 30. The degree of the opening movement of the valve 27 may be varied, as has 50 before been stated by the position into which the stop 30 has been previously adjusted, the valve being held open under normal conditions by the preponderance of weight of the valve 27 over the weight 29. It will 55 therefore be seen that the ease with which the valve 27 is closed or operated by the flow of fluid through the device, will depend upon the angle that the valve assumes when normally at rest, against the stop 30, and by 60 adjusting the stop 30 in the manner described, the valve will be correspondingly adjusted to meet the varying conditions of the flow of the gas in the different localities and when different types of meters are used. 65 This adjustment of the stop is ordinarily

used to limit the degree of opening movement of the valve 27 only at the time that the device is installed. As the gas passes through the device under normal conditions, the valve 27 will not be affected, but, however, when an abnormal flow of the fluid takes place at the discharge side of the device, the valve 27 will be automatically closed or moved by such abnormal flow against its valve seat 24 and will then be 70 retained in its closed position by reason of the incoming pressure of the gas. When the leak or abnormal flow in the outlet pipe is stopped, the valve 27 will automatically resume its normal position. This is due to 75 restoration of the pressure on the outlet side of the valve which may be accomplished by admitting fluid to that side of the valve, until the pressure thereon is equalized.

In order that the valve 27 may be operated 80 under normal conditions at the will of the operator, that is, when the pipes on the outlet side are intact or so nearly intact that the flow of gas is not sufficient to operate the valve 27, the stop 30 may be employed 85 and is adapted to be rotated in its bearing by the operation of the lever 34 in a direction to cause the high portion of the cam face 31 to ride against the valve 27 and thereby force it closed, and to rest against 90 the valve to hold it closed. In order to accomplish this, there is provided at any convenient point, an operating handle 38, which is connected with a shaft 39 journaled in the walls of a housing designated generally by 95 the reference numeral 40. This shaft 39 has a crank arm 41 which is connected by means of a link 42 with a slide or bar 43 movable in a guideway 44 within the housing. This slide passes through an opening in the bottom of the housing and through a tubular member or guide 45, and is connected to the lever 34 by means of a link 46 which is pivotally connected by one extremity to the slide or bar 43 and by its other extremity to 100 the lever 34, so that when the handle 38 is moved into the position shown in Fig. 7, the crank arm 41 will through the medium of the link 42, move the slide or bar 43 in the guide 44 to shift the latter which will 105 draw upon the link 46 to swing the lever 34, and this movement of the lever 34 will rock the stop 30 to cause its cam face 31 to move against the valve 27 and thereby close the latter. The parts will be held in this position by means of the link 42 and crank arm 110 41, which will move into such positions with respect to each other, that their points of pivotal connections will assume a substantially straight line as shown in Fig. 7, and 115 in order to arrest the parts when they do assume this position, a stop 47 is provided within the housing 40 against which the crank arm 41 will abut.

In order to prevent any strain on the parts 120

which might be occasioned by exerting a pressure on the handle 38 after the valve 27 has been closed, the slide or bar 43 is provided with a yielding section 48 (see Fig. 6) 70
 6 preferably in the form of an elastic member or coil spring which is interposed in the length of the slide and is connected by each extremity with the slide. In Fig. 10 there is shown a modified form of yielding section
 10 and in this form, one extremity of the elastic member 48 is connected by means of a flexible connection 49 such as cable, or the like, with the respective sections of the slide or bar 43. After the valve has once been closed
 15 in this manner, that is, manually by the operation of the handle 38, in order to re-set the stop 30 so as to permit the valve 27 to again open, the operator must first return the handle 38 to its normal position and then
 20 adjust the lever 34 back to the position in which the stop lug 36 will engage the stop 37.

In order to protect the lever 34 and to prevent unauthorized interference therewith, the lever together with the stop lug 36 and the stop 37, are housed within a removable casing 50 with which casing the tubular member 45 has connection, and the casing 50 is held in position by any suitable fastening device such as a padlock, which engages an 33 apertured ear or projection 51 that extends through a suitable opening in a portion of the wall of the casing, and which fastening device it is necessary to remove before the casing can be removed. With this improved 38 construction, it will be manifest that the stop 30 may be employed for two purposes, to wit: for controlling the degree of opening movement of the valve 27 and also as a means for manually and positively closing 43 the valve 27 when the fluid is passing through the device under normal conditions and for holding the valve closed. It will also be manifest that ready access may be had to the valve and to the valve seat as well 48 as to the interior of the valve chamber 19 by removing the fastening devices 17 which will permit the entire portion 16 together with the valve seat 24 and the valve, to be readily removed.

50 What is claimed as new is:

1. In a device of the class described, the combination of a casing having an inlet and an outlet, a valve in the casing adapted to be 55 automatically actuated by an abnormal flow of fluid to close the outlet, an adjustable cam forming a stop for regulating the opening movement of the valve, a lever exterior of the casing and means co-operating therewith for adjusting the position of said cam, said 60 lever being adapted for mechanically closing said valve without disturbing the pre-adjusted condition of the cam, and a connection for said lever exterior of the casing for mechanically actuating it to positively close 65 the valve.

2. In a device of the class described, the combination of a casing having an inlet and an outlet, a freely movable valve in the casing adapted to automatically respond to an abnormal flow of fluid to close the outlet, an independent adjustable cam within the casing adapted to engage the valve to positively close the latter, an exterior actuating member for said cam, an operating handle and a link having pivotal connections with the 70 said actuating member and handle, the points of pivotal connections of the link with the member and handle being adapted to be brought into a substantially straight line when the valve is closed to lock the parts 75 in such position.

3. In a device of the class described, the combination of a casing having an inlet and an outlet, a freely-movable valve in the casing adapted to be actuated automatically by 80 an abnormal flow of fluid to close the outlet, a cam independent of the valve within the casing adapted to engage the valve to positively close the latter, an actuating member for said cam, means for adjusting said actuating member and the cam to vary the position of said valve, an operating handle and a link having pivotal connections with said actuating member and handle, the points of 85 pivotal connections of the link with the member and the handle being adapted to be brought into a substantially straight line when the valve is closed to lock the parts in 90 such position, said actuating member having a yielding portion.

4. In a device of the class described, the combination of a casing having an inlet and an outlet, a freely movable valve in the casing adapted to be actuated by an abnormal 95 flow of fluid to close the outlet, a cam in said casing for positioning said valve to regulate the degree of responsiveness of said valve and constituting a stop for holding the valve in its adjusted position without interfering with its automatic operation, an arm on the outside of said casing connected to said cam for actuating it to mechanically close the valve, means co-operating with said arm for predetermining its position so that it may be actuated repeatedly without disturbing its adjustment, a remotely positioned operating device, connections attached to said device and said arm whereby said valve may be mechanically closed by 100 said device at a distance from the valve.

5. In a device of the class described, the combination of a valve casing having inlet and outlet ports, a freely movable valve pivoted in said casing and arranged to respond to an abnormal flow of fluid and close 105 said outlet port, a cam in said casing for positioning said valve to regulate the degree of responsiveness of said valve and constituting a stop for holding the valve in its 110 adjusted position without interfering with 115 said device.

its automatic operation, an arm on the outside of said casing connected to said cam for actuating it to mechanically close the valve, and means coöoperating with said arm for pre-determining its position so that it may be actuated repeatedly without disturbing its adjustment.

6. In a device of the class described, the combination of sectional casing having inlet and outlet ports, a freely movable valve pivotally suspended within said casing and arranged to automatically respond to an abnormal flow of fluid, a device within said casing but independent of the valve for positioning the valve to adjust its sensitivity and for holding it in its adjusted position without interfering with its automatic operation, a device on the outside of said casing connected to said inner device for actuating said inner device to mechanically close the valve instantly, and means for adjusting said outer device so that it may return to its pre-adjusted condition each time after the valve is mechanically closed.

7. In a device of the class described, the combination of a chambered casing having an inlet and an outlet, a freely movable valve positioned in said casing to close the outlet port and sensitive to an abnormal flow of fluid, and mechanism independent of said valve for adjusting its degree of sensitivity and for mechanically closing the said valve at will, said mechanism comprising an adjustable device within the casing against which the valve rests in its adjusted position, a device on the outside of said casing connected to said inner device for actuating said inner device to move the valve to a closed position, and means on the out-

side of said casing for stopping said outer device in its original position upon its return after it has been actuated.

8. In a device of the class described, the combination of a casing having an inlet and an outlet port, a valve in said casing adapted to respond automatically to an abnormal flow of fluid independent mechanism operable from the exterior of the casing for manually closing said valve independent of its automatic operation, and means for positioning said mechanism to adjust the valve and thereby permit the repeated manual operation thereof without altering the adjustment.

9. In a device of the class described, the combination of a casing having an inlet and an outlet, a valve in the casing adapted to be automatically actuated by an abnormal flow of fluid to close the outlet, independent adjustable means within the casing adapted to position the valve for automatic operation and to engage the valve to positively close the latter, a remote and manually operable actuating member for said independent means, and connections between the said actuating member and said means, whereby the valve may be positively closed repeatedly without disturbing the adjustment of said means.

In testimony whereof I have signed my name to this specification, in the presence of two subscribing witnesses, on this 27th day of October A. D. 1911.

ROBERT H. COWDREY.
